UNITED STATES PATENT OFFICE

WILLIAM HENRY DRESCHER, OF RICHMOND HILL, NEW YORK

STAIR PROTRACTOR

Application filed October 29, 1928. Serial No. 315,664.

The present invention relates to stair protractors and embodies an improved form of protractor for laying out stairs of any desired pitch, as well as providing a means for laying off the banisters without readjustment of the protractor. It is contemplated that the protractor may be used to lay off stairs upon stringers of considerable width and provision is made to accommodate conditions of this character as well as to permit the step and riser marking to be made at any point in the depth of the stringer. After an initial setting of the instrument, there is no need for further adjustment as long as the step and riser relationship of a stairway remains constant. By the construction provided herein, the protractor is easily and securely adjusted, no particular skill being required to effect the adjustment.

The invention will be understood more fully in connection with the accompanying drawings, wherein:

Figure 1 is a plan view showing a protractor constructed in accordance with the present invention and the manner of adjusting it for a given step and riser relationship.

Figure 2 is a plan view showing the manner in which the step and riser markings are applied to the stringer.

Figure 3 is a view in section, taken on line 3—3 of Figure 1, and looking in the direction of the arrows.

Figure 4 is a view in section, taken on line 4—4 of Figure 1, and looking in the direction of the arrows.

Referring to the above drawings, *a* designates a plate formed with sides *a'* and *a²* in ninety degree relationship, the lengths of these sides being immaterial. Preferably scales are inscribed upon these sides, starting from the intersection thereof and extending to the diverging ends as clearly shown in Figure 1. A rounded head portion *a³* is formed at the intersection of the sides, the center of the rounded portion lying in the intersection thereof. The rounded head portion is provided with an aperture *a⁴* through which a pivot pin *a⁵* passes.

An arm *b* is formed with a rounded socket portion *b'* which fits over the rounded head

a³ and is formed with an aperture *b²* through which the pivot pin *a⁵* extends. In this manner, the arm *b* is pivoted so that the axis thereof passes through the point of intersection of the sides *a'* and *a²*. A thumb nut *b³* is provided to secure the arm to the pivot pin *a⁵* and a second thumb nut *c*, engaging pin *c'*, is tightened to secure the arm in a desired position. The pin *c'* rides in a slot *a⁶* which is formed as an arc, the center of which is the pivot pin *a⁵*.

Apertures *d* and *e* are formed in the sides of the plate *a* and cooperate with apertures *d'* and *e'*, respectively, to form a square of the protractor. By removing the pin *c'* from the slot *a⁶* and inserting it through apertures *d* and *d'* or *e* and *e'*, respectively, a square may be formed of the instrument.

A stop *f*, formed of an angle iron *f²* may be secured to the arm *b* to permit the protractor to be used from the opposite side of the stringer. The stop *f* permits the protractor to be used from the other side of the stringer since its flanges may be adjusted so that it is parallel to the side of the stringer with the arm in such position that the edges *a'* and *a²* are at the desired angle of step and riser.

In this manner, the protractor may be held against the opposite side of the stringer by stop *f* and the desired angles drawn. Wing nuts *f'* and plate *f²* serve to clamp the stop to the arm *b* as clearly shown in Figure 3. As an additional feature, a hole *g* is formed in the arm at such distance from the aperture through which the pin *c'*

passes, that the last mentioned aperture may be used in conjunction with the pivot pin *a⁵* while the pin *c'* is used in conjunction with the aperture *g* to lengthen that portion of the arm *b* which extends outwardly from the intersection of the sides *a'* and *a²*. This provides a means for marking off stairs upon stringers of unusual depth.

It will be apparent that the protractor described above is capable of use with a given stair pitch without necessitating more than one adjustment. The initial adjustment may be made with great facility by applying a square to one side of the plate, as shown in Figure 1, and adjusting the arm so that the

lower edge thereof falls upon suitable points on the scales of the arms of the square to give the step and riser dimensions. For example, with the square as applied as in Figure 1, the lower edge of the arm is set on the calibrations 5 of the vertical portion of the square and 8 of the horizontal portion, thus indicating the adjustment of the protractor for laying off stairs, the steps and risers of which are 8 and 5, respectively. As will be quite apparent, the protractor is capable of use in connection with constructions of many specialized forms and the invention is not to be limited, save as defined in the appended claim.

I claim as my invention:

A protractor comprising a plate having two edges intersecting at right angles and being straight throughout the lengths thereof, a rounded head formed on the plate with the point of intersection of the outer edges as the center thereof, an arm extending beyond the plate on both sides of the head, means to pivot the arm to the head at a point lying in the median plane of the arm and the point of intersection of the edges, means to secure the arm to the plate in a desired position, an adjustable stop on the arm, and means to secure the stop at a desired angle with respect to the median plane of the arm.

This specification signed this 27th day of October, A. D. 1928.
